CONCRETE MOLD

Newell S. Shumway, Phoenix, Ariz.

Application July 3, 1946, Serial No. 681,297

4 Claims. (Cl. 25—118)

1

This invention pertains to cement molding devices.

More particularly my improvements concern molds for casting irrigation headgates from hydraulic concrete.

Heretofore, headgates have been made partially from concrete and partially from sheet metal. I have found however that they can be made in unit form from concrete, with all parts, including the gate slide ways, made from concrete.

The objects, therefore, are, first, to provide a mold adapted to form a head on a length of concrete pipe so as to provide an entrance area, a gate face, and slide ways on each side of the gate face.

A second object is to provide a mold having take-down side plates a contoured bottom and slidably removable slot forming elements removable thru one of the side plates; and

A third object is to provide a form box for casting gate heads having a metal base contoured to form a face for a gate head, and a boss for positioning a pipe on which the head is to be formed provided with notches to receive groove forming bars, and a peripheral rabbet adapted to position side plates; together with hinged removable enclosing side plates, and removable groove forming bars.

Other objects will appear hereinafter.

I attain the foregoing objects by means of the devices shown in the accompanying drawings in which—

Figure 1 is a perspective view of the assembled mold with a conduit pipe in place, and portions of the sides broken away to show interior construction;

Figure 2, a sectional elevation of the mold and pipe taken substantially on line 2—2, Figure 1, with concrete added;

Figure 3, an elevation showing the face of a gate head after being cast in the mold;

Figure 4, a section thereof taken on line 4—4, Figure 3;

Figure 5 is a plan thereof with the gate sectioned substantially in line 5—5, Figure 3;

Figure 6, a front view of a type of gate adapted for use in the head;

Figure 7, a side view thereof; and

Figure 8, a fragmentary view one corner of the mold box showing a side plate locking means.

Similar numerals refer to similar parts in the several views.

In general the mold box 2 is composed of a base 55 shown in Figures 6 and 7.

2

plate 3 of aluminum, a removable boxing 4 and sliding groove forming bars 27 and 28.

The rectangular base plate is contoured by a raised boss 10 to provide a gate face area recess 11 adjoined by an outer face forming area or flange 12 on each side and at the bottom. A rabbet 14 is formed around the outer edges of the mold to position the side plate members 16 and 26 of the boxing 4. The ends of these members are joined at three corners by flexible metal plates 17, and at the fourth corner by a hinge latch 18 having a removable pin 19 as shown in Figure 8. Bevel forming strips 20 are fastened along the upper and lower inside edges of plate members 16.

Side plate member 26 abutting the side of base 3 which forms the top of the head is pierced to receive groove forming flat bars 27 and 28.

The side edges of boss 10 are rabbeted as indicated by numeral 30, Figure 2, to receive the inner half of these bars as shown particularly in Figure 2. The bars, when in position for molding extend along the side edges of the boss 10 with the outer half of their edges protruding outward 25 from each respective edge.

Near the bottom forming ledge of the boss abutments 29 are added to form clearance areas 31 at the bottoms of the edges of the gate face. All edges of the boss may be smoothly rounded 30 or beveled, as desired. Likewise fillets may be added.

In use, a pipe 32 is set in the middle of boss 10 on a secondary or positioning boss 33.

The sides of the mold are assembled and bars 35 32 and 28 inserted into position as shown in Figure 1. The lower end of the pipe is then surrounded by a channel space on both sides and at the back which is to form the bottom of the head 35. This channel is then filled with concrete 36 which is well tamped and troweled along the top which forms the inner face 42 of the gate head 35.

After the concrete has set the mold is disassembled by first removing bars 27 and 28. Then pin 19 is removed to release the side plates 16. These are sprung outward slightly and raised over the top of the pipe 32. After the concrete is cured the head may be removed from base 3 and is ready for use. When cast the head has the form shown in Figures 3, 4 and 5. It is a rectangular block encasing the end of the pipe. The gate face 37 is set back from the outer face 38, and its enclosing sides 39 are provided with grooves 40 adapted to receive the flat gate 41 shown in Figures 6 and 7.

Having described my invention I wish to be limited only by the following claims.

I claim:

1. A cement mold for forming gate heads on the ends of cement pipes, comprising a rectangular open top box adapted to enclose the lower end of a pipe set vertically therein, said box including a rectangular base having a face, a rabbet formed around the edges thereof, edges defining the top, bottom, and sides of the gate head to be molded, and a rectangular faced boss formed thereon extending from the top defining edge on said base to a ledge set in from the gate head bottom defining edge, with the sides and ledge face of said boss extending upward and slightly inwardly from the face of said base and rabbets formed along the side edges thereof, together with enclosing plates adapted to form the top, bottom and sides of said gate head, hinged together at three corners and latched at one corner and adapted to rest in the rabbet formed around said base; said gate head top forming plate being pierced to receive groove forming bars; and groove forming bars extending thru said top forming plate and along the side edges of the face of said base boss with their outer edges extending beyond the top side edges of said boss, and their inner edges resting in said rabbets along the edges of said boss.

2. A cement mold for forming gate heads on the ends of cement pipes, comprising a rectangular open top box with removable sides adapted to enclose the lower end of a pipe set on end therein; said box including a rectangular base having edges defining the top, bottom and sides of the gate head to be molded, a flat upper face contoured to provide a rectangular upwardly extending boss having upstanding bottom and side faces and extending from said gate top forming edge of said base to a ledge forming face set in from the bottom defining edge of said base, a pipe positioning boss formed in the central portion of the upper face of said boss, rabbets adapted to receive and position groove forming bars, formed along the top adjacent the side faces thereof, and abutments extending outward from the side faces adjacent the lower ledge thereof; a side enclosure for said box composed of side plates fastened together with thin metal straps to form three flexible corner joints and a pin latch forming the remaining corner joint; and flat bars inserted thru and supported in the side plate on said top defining edge of said base extending into said box and resting in the rabbets on each side of said boss with their outer edges extending beyond the sides thereof to form gate grooves.

3. A cement mold for forming gate heads, having rectangular open top gate recesses on their outer faces with gate slide grooves at the edges thereof, on the ends of cement pipes, comprising a rectangular open top mold box in which said pipe may be placed on end, including a rectangular base plate having rabbets formed along the upper edges of its perimeter, a raised rectangular boss having a flat upper face and upstanding sides, one side being flush with the edge of the rabbet defining the top of said gate head, the sides adjacent thereto and the opposite end being set in on the face of the base plate from its edges to provide flanges to form the outer face of said gate

head, rabbeted grooves formed on the sides of the face of said boss to receive and position gate groove forming bars, and a circular boss formed on its upper face to position the end of a pipe set thereon; boxing enclosing the sides of said base plate including side plates adapted to rest in said edge rabbets hinged at three corners and latched at the fourth corner, holes formed in the boxing plate adjacent the flush side of said boss aligned with the rabbets on the sides thereof; and gate groove forming means consisting of flat bars inserted thru and supported in said plate adjacent the flush side of said boss, and positioned in the rabbets along the edges of said boss, with their outer lateral edges extending beyond the side faces of said boss.

4. A cement mold for forming gate heads with open top gate recesses on their front faces, on the ends of cement pipes consisting of an open top mold box, having removable sides, and a contoured bottom mold plate to receive and position a pipe therein; said mold box including, in combination, a rectangular bottom plate having top and bottom edges corresponding to the top and bottom edge faces of the gate head to be molded, and side edges corresponding to the sides of said gate head; means thereon for forming a recess on the outer face of the gate head to be molded including a rectangular boss, having substantially vertical side faces and extending inward from a vertical face flush with the top defining edge of said base plate, with its said side faces and bottom face set in from the edges of said base plate to provide flanges to form the outer face of said gate head, abutments formed on the inner portions of the side faces of said boss, to form clearance areas at the bottom of said gate recess, and rabbet grooves formed on the face of said boss along its lateral edges to receive and position gate guide groove forming bars, and rabbets formed along the edges of the perimeter of said base to position boxing plates; means for enclosing the sides of said mold including boxing plates hinged together at three corner joints, and latched at the fourth corner joint adapted to rest in the rabbets of said base; and means for forming gate guide grooves in the side edges of gate recess of the gate head to be molded, including flat bars positioned in the lateral rabbeted grooves on said boss, extending longitudinally outward thru aligned openings in the boxing plate enclosing the vertical face of said boss adjacent the top forming edge of said base, and having their lateral outer edges extending beyond the side faces of said boss.
